(57) **CLAIM**

The ornamental design for a reusable pizza container, as shown and described.

DESCRIPTION

FIG. 1 is a perspective view of the reusable pizza container, showing the top in its raised position and slightly separated from the container.

FIG. 2 is a perspective view of the reusable pizza container, with the lid in its closed position.

FIG. 3 is a top plan view of the container without the lid.

FIG. 4 is a bottom plan view of the container.

FIG. 5 is a rear elevational view of the container.

FIG. 6 is a front elevational view of the container.

FIG. 7 is right side elevational view of the container; and,

FIG. 8 is a left side elevational view of the container.
